TARGET TRAP

Willis J. Sutcliffe, Waterloo, Iowa

Application January 25, 1933, Serial No. 653,380

3 Claims. (Cl. 124—3)

My invention relates to improvements in target traps, and the object of my improvement is to improve the construction of the target throwing arm of such a trap, by rendering its supporting means adjustable, whereby greater efficiency is given thereto in the varying of the directions of propulsion of targets.

This object I have accomplished by the means which are hereinafter described and claimed, and 10 which are illustrated in the accompanying drawing, in which Fig. 1 is a side elevation of a marksman's target trap, with parts removed or in section; Figs. 2 and 3 are respectively plans of the top and bottom of the target throwing arm on 15 an enlarged scale, and Fig. 4 is a cross section thereof taken on the broken line 4—4 of said Fig. 3.

Fig. 1 is a view of a well known target trap having a metal base block 2 on a plank 1, and centrally vertically socketed to seat rotatably horizontally the depending stem or rock-shaft 4 of a rock-body 3 set thereon. The numeral 8 denotes another rock-body pivotally mounted on the rock-body 3 on a pintle-bolt 5 with clamping-nut, 20 to secure it in an adjusted degree of vertical tilt longitudinally. The rock-body 8 has an arcuate slot 7 with radius to said pintle-bolt 5, and a bolt 6 with a clamping-nut thereon traverses the slot and an aperture in the body 3 to be secured 25 by the nut when the body 8 has been adjustably tilted relative to the body 3.

The numeral 12 denotes a U-shaped trap frame for holding the operative mechanism by which the target throwing arm 25 is actuated. 30 This mechanism, with elements omitted, may be a rock-shaft 22 upon whose top the arm 25 is secured, a sprocket-wheel 21 carrying a sprocket-chain 20 end-connected to a rockable body 18 and the latter pivoted swingingly at its top to the 40 upper member of the frame. A traction-rod 16 for said chain connected to the body 18, an anchoring rod 19 fixed in one end of the frame, and a coiled tension spring 17 connected between said rod 19 and the rock-shaft 22 in a well-known way 45 not shown. The frame 12 has at or near one end on its lower parallel frame member lugs or projecting parts 15 and 13 apertured in alignment to seat therebetween a pintle rod 11.

The rock-body 8 has at the top the longitudinally spaced apertured lugs 9 and 10 mounted loosely on the shaft or rod 11, whereby the frame 12 is swingably mounted on said rod and body 8. The projection or lug 13 on the frame 12 is fixed 50 thereon to depend alongside the rock-body 8, and has at its lower end an arcuate slot not shown

traversed by a threaded stem 14 and secured by a clamping-nut, whereby said frame may be held at a desired degree of lateral tilting relative to the body 3, but the slot is not shown, as the subject-matter of this construction to permit 60 such lateral adjustable tilting of said frame is the object of a co-pending application for patent.

The rock-shaft 22 is seated rockably in alined bearings such as at 23 of the frame 12. Referring now to said Figs. 2 to 4 inclusive, the throwing plate 27 is of approximately oblong shape, having near one longitudinal edge a short longitudinally disposed slot 29, and having on its upper face, top and bottom of the edge from said slot spaced fixed standards 35 along and upon which are 70 secured a rigid bar 36 of U-shaped cross section and opening toward said slot 29, and preferably with a strip of elastic rubber 37 mounted within its deep groove, to project laterally therefrom. On its bottom the plate 27 has spaced parallel 75 ribs to seat therebetween the fitting arm 25 secured by screws or other fastening means. This arm has without said plate an apertured head 24 mountable upon the top part of the rock-shaft 22, and secured thereto by a set-screw. 80

Referring to Figs. 3 and 4, the numeral 30 denotes a rib on said plate set off from but parallel to said ribs 26, and narrowly spaced from the rib 30 is another rib 31 parallel therewith, and the plate has also several spaced lugs or teeth 32 85 alined with the rib 31. One of the parallel ribs first mentioned on the plate 27 is lengthened at 34 to extend almost the entire length of the plate.

The numeral 38 denotes a rock-shaft rod seated in the bearing channel between the ribs 30 and 90 31 and retained therein by a split-key 33 traversing both transversely across the rod. One end part of this rod is bent doubly with an arm 39 angularly having a weight 40 on its free extremity. 95

The opposite end part of the rock-shaft 38 is bent at a right angle at 41 to be seated in any aperture between the teeth 32 adjustable when the shaft is suitably longitudinally displaced in its bearing channel. The arm 41 is again bent 100 upwardly with its termination 43 normally traversing the slot 29 of the plate 27 to project above the upper surface of the plate, due to the weight 40 on the other arm 39. Preferably there may be mounted on the arm 41 a short rubber sleeve 105 42 to contact cushioningly across and with a long variously curved rib 28 on the bottom of the plate 27, as a stop.

A target, such as the well-known frangible clay turreted disk type, may be placed upon the 110

throwing plate 27, after the frame 12 has been adjusted as desired for longitudinal and lateral tilting by the means above described, and to engage with the outer edge of the cushioning rubber strip 35 and with the upwardly projecting termination 43 of the crank-arm 41. When the trap mechanism is operated to release and swing the resiliently controlled throwing arm 25, the target disk rolls lengthwise along the plate 27 outwardly along the rubber strip 35 and while in rapid rotation is projected into the air at a certain angle to the trap.

My invention resides in the adjustability of the extremity of the crank arm 41 and 43 longitudinally of the plate 27, as the crank part 41 is set into one or another of the recesses or openings between the teeth 32. According to the greater or less travel of the target along the plate 27, because of such an adjustment of the part 43, the target is rotated more or less rapidly and therefore is ejected from the plate later or sooner relatively to the length of swinging travel of the plate at the moment of ejection of the target, and whereby the target is projected in paths of different angles relative to the trap. It will be understood that when the swinging plate 27 has attained sufficient speed the centrifugal force acting upon the weight 40 will swing upwardly the arm 39 while simultaneously lowering the other arm 41-43 with the end of the part 43 below the top of the plate 27 at a time when the target should be ejected from the plate, and thus the target is released for such a variable throw without being prematurely shattered on the plate.

Various modifications in the details of construction and arrangement of parts of the apparatus and its connections may be made without departure from the principle and scope of the invention as defined in the following claims.

Having described my invention, what I claim as new, and desire to secure by Letters Patent, is:

1. In a target trap, in combination, a target carrying and delivering device mounted rockingly thereon, comprising a plate having a straight edge element raised along one longitudi-

nal edge thereof the plate having a longitudinally directed slot opposite said element, and a rock-body mounted on and under the plate for longitudinal adjustments therealong, one termination of the rock-body normally traversing said slot upwardly to provide a withdrawable stop thereabove, and the other termination of the rock-body shaped and weighted to rock under the influence of gravity when the plate is rocked in one direction, to withdraw the stop part below the upper surface of the plate and release a target stopped thereagainst, and against the said straight edge element. 80

2. In a target trap, in combination, a target carrying and delivering device mounted swingingly thereon, and comprising a plate having a longitudinal marginal stop wall, and a rockable member mounted longitudinally under said plate, having one end bent upwardly to extend above the plate to provide a removable stop for the target, and having the other end bent reversely to the first end and weighted, whereby when the plate is swung in one direction the rod is rocked by its weighted end part to withdraw its first stop end from the path of projection of the target. 90

3. In a target trap, in combination, a target carrying and delivering device mounted swingingly thereon and comprising a plate having a marginal wall, and a rockable rod mounted longitudinally on the under face of the plate, having a cranked arm rising normally above the top of the plate to serve as a stop for a target which also engages said marginal wall, said rod having an oppositely projecting crank arm at its other end weighted to rock the rod when the plate is swung to withdraw said stop arm below the plate, the under face of the plate having a plurality of spaced projections parallel with the rod, and the rod being longitudinally adjustable alongside said projections to permit its stop arm crank to be seated in any interspace of the projections to allow a target to be varied in position longitudinally along the plate in engaging the stop arm in an adjusted position along the plate. 100
